PNEUMATIC TIRE TREAD AND BUTTRESS

James F. Newman, St. Clair Shores, Mich., assignor to
Uniroyal, Inc., New York, N.Y.

Filed Aug. 15, 1969, Ser. No. 18,704

Term of patent 14 years

Int. Cl. D12—15

U.S. Cl. D90—20

FIG. 1 is a perspective view, partly schematic, of a pneumatic tire tread and buttress embodying my new design, it being understood that the pattern is repeated throughout the circumference of the tread and buttress, as shown schematically by solid lines;

FIG. 2 is an enlarged, fragmentary plan view of the tread of FIG. 1;

FIG. 3 is an enlarged, fragmentary elevational view of the buttress of FIG. 1;

FIG. 4 is a fragmentary sectional view, taken substantially on the plane indicated by line 4—4 of FIG. 2;

FIG. 5 is a fragmentary sectional view, taken substantially along the line 5—5 of FIG. 3; and

FIG. 6 is a fragmentary sectional view, taken along line 6—6 of FIG. 3.

I claim:

The ornamental design for a pneumatic tire tread and buttress, substantially as shown and described.
